Primary Examiner — Karen E Eldridge Powers(74) *Attorney, Agent, or Firm* — Davis Wright Tremaine LLP; Heather M. Colburn**CLAIM**

The ornamental design for a vibrating skin cleansing brush, as shown and described.

DESCRIPTION

FIG. 1 is a top right side perspective view of a vibrating skin cleansing brush showing my new design.

FIG. 2 is a bottom left side perspective view thereof.

FIG. 3 is a front elevation view thereof.

FIG. 4 is a right side elevation view thereof.

FIG. 5 is a left side elevation view thereof.

FIG. 6 is a rear elevation view thereof.

FIG. 7 is a top plan view thereof; and,

FIG. 8 is a bottom plan view thereof.

The broken lines represent portions of the vibrating skin cleansing brush that form no part of the claim.

1 Claim, 7 Drawing Sheets(56)
